US0D1057843S

(12) **United States Design Patent** (10) Patent No.: **US D1,057,843 S**
(45) Date of Patent: ** Jan. 14, 2025

(54) **ELECTRIC SCOOTER**

(71) Applicant: **Ninebot(Hangzhou) Tech Co., Ltd.**,
Hangzhou (CN)

(72) Inventor: **Jinbo Shao**, Zhejiang (CN)

(**) Term: **15 Years**

(21) Appl. No.: **35/516,187**

(22) Filed: **Jan. 16, 2023**

(80) **Hague Agreement Data**

Int. Filing Date: **Jan. 16, 2023**

Int. Reg. No.: **DM/226389**

Int. Reg. Date: **Jan. 16, 2023**

Int. Reg. Pub. Date: **Feb. 10, 2023**

(30) **Foreign Application Priority Data**

Jul. 28, 2022 (CN) 202230486076.5
